By Wallace R. Lane Atty.

UNITED STATES PATENT OFFICE.

HARRY W. EMBRY, OF LOUISVILLE, KENTUCKY, ASSIGNOR TO GENERAL BOX COMPANY, OF CHICAGO, ILLINOIS, A CORPORATION OF DELAWARE.

BOX CLEAT.

Application filed September 1, 1926. Serial No. 132,913.

This invention relates to improvements in box cleats and has for its object to provide a new and improved cleat for use in fabrication of wire bound boxes. Other objects are to provide a cleat which, when incorporated with the other elements of a wire bound box or the like, will permit relatively easy folding of the blank to box form and eliminating or greatly decreasing the tendency in present day cleats to split off or break during folding; to provide a cleat of this character which will render the boxes stronger, particularly at the corners, than present day boxes; to provide a new cleat having the above advantages which may be easily manufactured on present day machines; to provide such a cleat which will permit folding of the box blank in which it is included, even though staples may have been driven into the interfitting portions of the cleats; to provide a cleat of this character which will permit stapling of the binding wire closer to the corners of the box than is permissible in present day practice; and, in general, to provide a device which will accomplish the above and other advantages.

In the accompanying drawing, I have illustrated an embodiment of my invention, in which—

Fig. 1 is a plan view of the inner side of a box blank utilizing my improved cleat.

Fig. 2 is a bottom elevation of the cleat drawn to an enlarged scale.

Fig. 3 is a side elevation of the same, the associated boards or strips being indicated in dotted lines.

Fig. 4 is a section along the line 4—4 of Fig. 3 the portion of end and side boards being illustrated in assembled relation.

Fig. 5 is a disassembled view of another form of the cleat showing the cooperating ends of two cleats shaped slightly differently from the cleat shown in Fig. 2.

In the drawing, 10 illustrates a box blank formed on the veneer or other strips or boards 11 secured to cleats 12 by staples or the like driven through binding wires 13, the boards 11 and into the cleats 12 in well known manner.

In the manufacture of these blanks, as is well known, the cleats 12 are properly positioned and slightly spaced and the boards or

strips 11 are stapled together as stated, the same staples being utilized to secure the binding wires 13 to the blank.

55

The cleats 12 are formed of strips of wood or the like having V-shaped notches 12^a at one end formed by the sides 12^b diverging outwardly from the flattened base or bottom 12^c. The other ends of the cleats 12 are formed with the wedge or V-shaped tongues or tenons 12^d tapering from the relatively wide top 12^e to the narrow bottom 12^f, which is also flattened as illustrated in Fig. 2, for example. The top 12^e is of a width equal to or slightly less than the width of the notch 12^a in the other end.

60

65

After formation of the blank, illustrated in Fig. 1, when it is desired to assemble or complete the box, the sides are folded around and end boards 14 are fitted against and secured or not as desired to the cleats 12. During this folding of the sides the tongues 12^d of the cleats will move into the adjacent notches or recesses 12^a of the adjacent cleats 70 and this entrance, as will be obvious, is without interference due to the considerable difference in width between the narrow edge 12^f of the tongues and the wide opening of the notches 12^a. The flattened bases 12^c of the notches and the flattened edges 12^f of the tongues prevent cutting or splitting of one cleat by the tongue of the other should too much force be exerted upon the corner of the box in its folding. It is desirable to 75 make the tongues 12^d of such size as to move easily to seated position in accommodating notches 12^a without sufficient clearance to permit objectionable play after folding.

80

85

Nevertheless, should the staple ends protrude through the sides of the tongues 12^d or the sides 12^b of the notches, the tapered construction of the tongues and notches will permit the accommodation of these protruded staple ends and the folding of the box will 90 not be seriously interfered with.

There is no danger of interference with the entrance of the tongue into the notches as is frequently the case in present day mortise and tenon cleat construction as will be 100 apparent and little or no force is required in the folding operation to ensure seating of the tongues in the notches. At the same time, as stated, should force in excess of that

required be applied wedging or splitting at the sides of the notches is prevented by the flattened contact surfaces 12^c and 12^f.

Another advantage resides in the tapered 5 construction of the sides of the notches 12^a which, increasing in thickness from the entrance to the enclosed end, present an increasing resistance to any splitting or wedging action.

10 The relatively wide top of the tongue 12^d permits driving of staples without destruction and permits stapling of the wires close to the corners of the boxes which does away with any possibility of the box wires slipping 15 over the corners under stress or contact from other boxes when loaded.

If desired, the cleat may be manufactured in the form shown in Fig. 5 in which the end 20 of the tenon is slightly rounded and the seat 20 of the mortise is correspondingly rounded. This construction will give approximately the same results as are obtained from the cleat shown in Fig. 2, as it is found that this 25 cleat also will not have a tendency to split since there is enough wood at the bottom of the mortise to counteract such an effect. It is contemplated that the bottom of this recess will be substantially flat.

My improved cleat is also susceptible of 30 economical manufacture.

It will be obvious that my invention is susceptible of modification and I do not wish to be restricted to the form shown and described except as defined in the appended 35 claims.

What I claim is:—

1. A box cleat having a tongue at one end and a recess at the other, said tongue and recess having converging sides, the side of one converging in a plane transverse to the plane 40 of convergence of the other.

2. A box cleat having a tongue at one end and a recess at the other, said tongue and recess having pairs of converging sides, the sides of the tongue converging in planes 45 transversely of the cleat and the sides of the recess converging in planes longitudinally of the cleat.

3. A box cleat having a tongue at one end and a recess at the other, said tongue and recess having converging sides, the sides of the tongue being angularly disposed relative 50 to the sides of the recess.

4. A box cleat having a tongue at one end and a recess at the other, said tongue and 55 recess having pairs of converging sides, the sides of one pair being at an angle to those of the other.

5. A box cleat having a tongue at one end and a recess at the other, said tongue and 60 recess having pairs of converging sides, corresponding sides of one being at an angle to those of the other.

6. A box cleat having a tongue at one end and a recess at the other, said tongue and 65 recess each having a tapered side, the tapered side of the tongue tapering transversely of the cleat and the tapered side of the recess tapering longitudinally of the cleat.

In witness whereof, I hereunto subscribe 70 my name to this specification.

HARRY W. EMBRY.
